UNITED STATES PATENT OFFICE.

ELEAZER KEMPSHALL, OF NEW YORK, N. Y., ASSIGNOR TO KEMPSHALL SUPPLY COMPANY, A CORPORATION OF NEW JERSEY.

SPINNING-ROLL.

1,074,504.

Specification of Letters Patent. Patented Sept. 30, 1913.

Application filed January 29, 1913. Serial No. 744,979.

To all whom it may concern:

Be it known that I, ELEAZER KEMPSHALL, a citizen of the United States, residing at New York, in the county of New York and State of New York, have invented certain new and useful Improvements in Spinning-Rolls; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to rolls for spinning machines.

The object of the invention is to provide a slow yielding mass of material, and an interposed binder of material having a less 20 tendency to rebound or yield than either the outer coating of pyroxylin, or the inner material forming the base.

My invention therefore is primarily directed to a roll constructed of such material 25 as will slowly yield effectually to avoid breaking or displacing the thread when passing between a pair of rolls.

In the drawings: Figure 1 is an elevation of a pair of rolls, one of the latter being 30 broken away to illustrate the invention. Fig. 2 is an enlarged detail cross section of one of my improved rolls.

1 indicates a shaft, 2 a metal core on the shaft. Around the metal core is a base of 35 slow yielding material 3, felt being preferably employed. The base of felt is of substantial thickness, and is in a semi-compressed condition to form a tight grip on the metal core. To hold the base solid on the 40 core, and at the same time add to the slow action of the felt, I incase the latter with a thin binder of leather, indicated at 5. The leather is stretched tight around the felt and clamps the same on the core, and prevents 45 slipping which frequently occurs when knots are formed in the thread.

The leather binder is coated with pyroxylin, indicated at 8, and when the latter is applied it takes into, or packs into the interstices of the leather, and forms a tight grip. 50 The materials, base, and coating form a homogeneous body of yielding material, which will slowly rebound to its normal position after the thread passes from between the roll.

55 In a companion application, executed of even date, I have described and claimed a base of felt, but for a certain class of thread I find it expedient to provide a mass which will respond even slower than a body of 60 fabric. Furthermore, when the pressure between the rolls is very great, it is essential that an effective binder between the pyroxylin and felt be provided. I find that this binder must be of such material as will 65 slowly yield, and must be capable of taking the pyroxylin in its outer surface, and at the same time it must possess the necessary strength. Leather has all of these essentials, so that in addition to a binder, the leather 70 acts with the felt as an effective means to make the mass slowly yield without a rebound.

Having described my invention, what I 75 claim is:

1. A roll comprising a core, a layer of thick fabric on the core, a binder of leather on the fabric, and a coating of pyroxylin on the leather.
2. A roll comprising a core, a thick layer 80 of felt on the core, a binder of leather around the felt, and a coating of pyroxylin around the leather, the pyroxylin being embedded in the interstices of the leather.

In testimony whereof I have signed my 85 name to this specification in the presence of two subscribing witnesses.

ELEAZER KEMPSHALL.
